UNITED STATES PATENT OFFICE.

VICTOR VON SCHLEGELL, OF NEW YORK, N. Y., ASSIGNOR TO HALE AND KILBURN COMPANY, OF PHILADELPHIA, PENNSYLVANIA, A CORPORATION OF DELAWARE.

CAR-SEAT.

1,196,187.

Specification of Letters Patent. Patented Aug. 29, 1916.

Application filed July 17, 1912. Serial No. 709,943.

To all whom it may concern:

Be it known that I, VICTOR VON SCHLEGELL, a citizen of the United States, residing at New York, in the county of New 5 York and State of New York, have invented certain new and useful Improvements in Car-Seats, of which the following is a specification.

This invention relates to car-seats of the 10 type in which the back-cushion is mounted stationarily at the rear edge of the seat-cushion, the seat being of the non-reversible type.

The invention is directed to the provision 15 of an improved form of support for the end of a seat of this type which supports, while possessing the high degree of strength required in a support for this use, is of very light weight and is of such size and shape 20 that it will not restrict the freedom of entrance to the space directly in rear of the seat.

The further object of the invention is to 25 provide a support of this type which may be manufactured at low cost and which is of attractive appearance.

In accordance with the invention the support for the end of the seat- and back-cushions is formed primarily from a single piece 30 of sheet-metal pressed into form and having a base-portion which is secured to the floor, a body portion having a flanged and inclined upper edge adapted to receive and support the seat-cushion and a back-supporting arm extending upwardly from the body-portion and adapted to have the end 35 of the back-cushion secured thereto. This seat-supporting member, being made of sheet-metal, may be pressed into form at 40 relatively low cost and is of light weight. In order to secure the requisite degree of strength a second sheet-metal piece is combined with the first one, this second piece extending over the angle in the first piece at 45 the junction of the body-portion and the back-supporting arm so as to form a reinforce at this point where the support is subjected to the greatest strain and where it is necessary that the support be of relatively 50 small size so as not to encroach upon the space directly in rear of the seat. Preferably, the support is formed of two pressed sheet-metal pieces secured together at their edges and both of them formed into the 55 base-portion which is secured to the floor

and the body-portion of the support. When this construction is employed the inner piece is extended from the body-portion upwardly over the lower end of the back-supporting arm so as to constitute the necessary 60 reinforce but it is not extended all the way up to the end of the back-supporting arm, this arm being formed from the outer piece only and being provided with a flange along its rear edge which flange coacts with the rear 65 face of the back-cushion when the arm proper is secured to the edge of the back-cushion. Either or both of the two plates have their body-portions so shaped as to provide an inclined cushion-supporting arm or surface 70 upon which the seat-cushion is adapted to rest. In the preferred embodiment of the invention, an inwardly extending flange is provided on the outer sheet-metal piece for this purpose and this flange may be braced by a 75 coacting flange on the upper edge of the body portion of the inner piece.

The preferred embodiment of the invention is illustrated in the accompanying drawings in which—

Figure 1 is an end view of a car seat constructed in accordance with the invention, Fig. 2 is a front view of the seat broken away and sectioned in part, Fig. 3 is a section on line 3—3 of Fig. 1, Fig. 4 is a section on line 4—4 of Fig. 1, Figs. 5 and 6 are sectional views on lines 5—5 and 6—6 respectively of Fig. 1, Fig. 7 is an end view of a modified form of seat, Fig. 8 is a section on line 8—8 of Fig. 7, Figs. 9 and 10 are detail sectional views on lines 9—9 and 10—10 respectively of Fig. 7, Fig. 11 is an end view of another form of car-seat constructed in accordance with the invention, and Figs. 12, 13 and 14 are sectional detail 90 views on lines 12—12, 13—13 and 14—14 respectively of Fig. 11.

Referring first to Figs. 1 to 6, the seat consists of a seat-cushion 15 and a back-cushion 16 having their ends mounted upon metallic supports. One of these supports may be used at the aisle end of the seat and the opposite end of the seat may be supported on the wall of the car or two of the supports may be employed at the two ends of the seat as shown in the drawings. The support consists of two pieces of sheet-metal cut to the desired configuration, pressed into form and secured together at their edges. These two pieces are so shaped as to provide 110

a base-portion 17 flaring downwardly and adapted to be secured to the floor of the car, a body-portion 18 on the upper edge of which the seat-cushion 15 is adapted to rest, and 5 an upwardly extending back-supporting arm 19 to which the end of the back-cushion 16 is secured. The shape of the outer-sheet metal piece 20 is shown in Figs. 1 and 2. At the upper edge of the body-portion of this piece 10 20 an inwardly extending flange 21 is provided which flange is inclined in the direction of its length. The lateral edges of the body-portion are also inclined, as shown at 15 22, to stiffen the construction and give it a more finished appearance. The lower portion of the back-supporting arm 19 is also provided with flanges 23 and 24 (Fig. 6) but the flange at the forward edge of this arm is discontinued at a point immediately below 20 the edge of the back-cushion 16. The flange 24 at the rear edge of the back-supporting arm 19, however, is extended up to the upper end of the arm 19 as shown in Fig. 2. The inner plate 25 of the seat-support is shaped 25 to provide a body-portion corresponding to the body-portion of the outer plate and these two plates are secured together at the lateral edges. The plate 25 has a flange 26 at its upper edge which flange abuts against the 30 flange 21 on the outer plate 20 and is secured thereto so as to make the flange 21 more rigid as this flange forms the support for the seat-cushion. The lower ends of the two plates are shaped in any suitable manner to form 35 the base-portion of the seat-support; in the present instance, this base-portion is shown as consisting of two tubular legs but it will be understood that a single leg or other suitable form of base-portion may be employed 40 if desired. Between the two legs the outer plate 20 is preferably provided with an inwardly directed flange 27 which serves to further stiffen the construction and enhance the appearance.

45 The inner plate 25 is not extended up to the upper end of the back-supporting arm 19 but is extended far enough to overlap the lower portion of the arm 19, its upper end being indicated at 27' by the dotted line on 50 Fig. 1. This extension 28 (Figs. 5 and 6) extends over the angle in the outer plate 20 at the junction of the body-portion and the back-supporting arm of the seat-support and its edges are secured, preferably by welding, to the edges of the flanges 23 and 24 on the outer plate 20 so that this extension 28 of the inner plate 25 forms a reinforce 55 for the angle in the seat-support. At this angle the seat-support is of box-section as 60 shown in Figs. 5 and 6 as in this way great strength is obtained at this point which is subjected to the greatest strain in use and at the same time the dimensions of the support at this point are kept so small that the support 65 offers no obstruction to free entrance

to the space immediately in rear of the seat. The edges of the two pieces 20 and 25 forming the seat-support are preferably welded together as in this way a strong joint between them is effected and the structure is 70 given a finished appearance. A pin 29 is provided in the flange 21 at the upper edge of the body-portion of the support. The seat-cushion 15 bears upon this flange on the body-portion with its end extending beyond the support as in this way the seat-cushion 75 may be made of the maximum length. The back-cushion 16 has its end secured to the back-supporting arm 19 with its rear face bearing against the flange 24 on the arm 19. 80 The back-cushion 16 is thus of slightly less length than the seat-cushion 15 so that the aisle at the end of the seat is of greater width above the seat-cushion. If desired, the seat-support as a whole may be curved as shown 85 in Fig. 2 so that the base portion lies inwardly from the general plane of the support.

A slightly modified form of the seat-support above described is shown in Figs. 7 to 90 10 inclusive. The modifications here shown will be apparent from the drawings in connection with the above description. In this seat-support the inner plate 25 has its edge bearing upon the flange 27 on the outer plate 95 20 between the legs, whereas in the construction shown in Fig. 2, the inner plate has a flange at its lower edge which flange bears on the flange 27 of the outer plate and is secured thereto. In the form shown in 100 Figs. 7 to 10, the legs are of tubular form as shown in Fig. 10 instead of being flat on the inner side as shown in Fig. 4. If desired, the two legs of the form shown in Figs. 7 to 10 may be pressed to tubular form 105 from separate pieces of sheet-metal and thereafter welded to the lower end of the body-portion of the seat-support, but preferably the two pieces forming the seat-support are combined to form the leg by welding 110 their abutting edges together.

Referring now to Figs. 11 to 14 inclusive, a further modification of the structure will be described. In this form of the seat-support the latter is not curved but lies in the 115 same general plane throughout. Both of the two pieces employed in the construction of the support extend all the way down to the floor and have their edges welded together.

Having described my invention, what I claim as new therein and desire to secure by Letters Patent of the United States is:

1. A car-seat comprising a support consisting of two pieces of sheet-metal, pressed into form and secured together, both of said pieces being formed into a flaring portion at the lower end of the support adapted to be secured to the floor and a body-portion having an upper, inclined, cushion-support. 125 130 135

ing member, a seat cushion mounted upon the same with its end extending beyond the same, said support also having a back-supporting arm extending upwardly to the rear 5 of the seat cushion, from the outer one of said pieces, formed integral with said piece and having a flange at its rear edge, an integral extension on the inner one of said pieces secured to the lower end of said arm, 10 and a back-cushion secured to said arm, substantially as set forth.

2. A car seat comprising a seat cushion and a back cushion, and a support for one end of each of the same, consisting of a single 15 piece of sheet-metal pressed into form and having a base-portion adapted to be secured to the floor, a body-portion having an inwardly extending flange at its upper edge, on which said seat-cushion is supported, and a back-supporting arm extending upwardly from the base portion and to the rear of the seat cushion, and a second sheet-metal piece secured to the base portion 20 of said first piece, having a flange coacting with and stiffening said body-flange of said first piece, and having an upwardly directed extension, overlapping the lower part of said back supporting arm and secured thereto to form therewith a box-sec- 25

tion at the junction of the arm and body portion of said first piece, substantially as set forth.

3. A car seat comprising a seat cushion and a back cushion, and a support for one end of each of the same, consisting of a single 30 piece of sheet-metal pressed into form and having a base-portion adapted to be secured to the floor, a body-portion having an inwardly extending flange at its upper edge, on which said seat-cushion is supported, and a back-supporting arm extending upwardly from the base portion and to the rear of the seat cushion, and a second sheet-metal piece secured to said first piece to stiffen the same, having a flange coacting 35 with and contacting said body-flange of said first piece, and having a portion rising above said body-portion, overlapping the lower part of said back-supporting arm and secured thereto at its edges, to reinforce the junction of the arm and body portions of said first piece, substantially as set forth.

This specification signed and witnessed this 11th day of July, 1912.

VICTOR von SCHLEGELL.
